(57) **CLAIM**

The ornamental design for a fertility awareness bracelet, as shown and described.

DESCRIPTION

FIG. 1 is a top perspective view of a fertility awareness bracelet, showing my new design;

FIG. 2 is a right side elevation view thereof;

FIG. 3 is a left side elevation view thereof;

FIG. 4 is a front side elevation view thereof;

FIG. 5 is a rear side elevation view thereof;

FIG. 6 is a top plan view thereof;

FIG. 7 is a bottom plan view thereof;

FIG. 8 is a bottom perspective first view thereof;

FIG. 9 is a bottom perspective second view thereof;

FIG. 10 is a top perspective view of the fertility awareness bracelet of FIG. 1 shown in a state of use; and,

FIG. 11 is a bottom perspective view of the fertility awareness bracelet of FIG. 1 shown in a state of use.

The broken lines in the drawings represent portions of the fertility awareness bracelet and form no part of the claimed design. The broken lines in FIGS. 10 and 11 showing a human arm represent environmental subject matter only and form no part of the claimed design.
